PROCESS OF PRODUCING PYRAZINAMIDE

John S. Webb and Herbert G. Arlt, Jr., Warren Township, Somerset County, N. J., assignors to American Cyanamid Company, New York, N. Y., a corporation of Maine

No Drawing. Application June 17, 1952,
Serial No. 294,073

12 Claims. (Cl. 260—250)

This invention relates to an improved process of preparing pyrazinamide.

Pyrazinamide has acquired considerable practical importance in recent years by reason of its tuberculostatic activity. The processes of producing pyrazinamide have been cumbersome and have required a number of steps which have increased the cost of production materially. In general in the past, when starting with pyrazine-2,3-dicarboxylic acid, the usual practically producible intermediate, it has been necessary to decarboxylate partially to pyrazinoic acid. This step has required considerable care, as high temperatures tend to carry the decarboxylation all the way to pyrazine. After the pyrazinoic acid has been obtained, it was esterified, usually with methyl alcohol, because the ordinary processes of amidation resulted in excessive losses due to decarboxylation to pyrazine. The ester was then amidated by conventional means. In other words, in the past it has been necessary to carry out three separate reactions under different conditions and each resulting in a certain loss of yield. As a result, the cost of pyrazinamide has been very high; and its production has involved considerable operating difficulties and other problems, due to the necessity of obtaining not only adequate yields of pyrazinamide but a high grade, because of the rigid requirements for purity entailed in the pharmaceutical use of the end product.

In our copending application Serial No. 294,072, filed June 17, 1952, we have described and claimed an improved process of amidating pyrazinoic acid. In this process, pyrazinoic acid or its ammonium salt is heated at high temperature with urea. The urea stabilizes the pyrazinoic acid against decarboxylation and although the temperatures are far above those which are ordinarily considered safe for amidation of the acid, good yields of pyrazinamide are obtainable. Our improved process, referred to above, still suffers, however, from the fact that it is first necessary to prepare pyrazinoic acid or the ammonium salt of pyrazinoic acid, and then to effect the amidation. In other words, while we have reduced the necessity of esterifying pyrazinoic acid, there is still required two separate steps under entirely different reaction conditions in order to go from the pyrazine-2,3-dicarboxylic acid or ammonium salts to the pyrazinamide. While our improved process has removed many of the objections from the step of amidating the pyrazinoic acid, it of course does not help in the slightest in the problem of partial decarboxylation of pyrazine-2,3-dicarboxylic acid or its salts.

We have found, according to the present invention, that it is not necessary to start from pyrazinoic acid. On the contrary, we are able to eliminate entirely the first step of decarboxylation of the pyrazine-2,3-dicarboxylic acid to pyrazinoic acid; and this delicate step is entirely eliminated. We have found that if we fuse urea with pyrazine-2,3-dicarboxylic acid or its ammonium salt, pyrazinamide is obtained directly in good yield. In other words, our present improvement eliminates one of the separate steps of our former process without eliminating its function, and permits operating in a single piece of chemical equipment, under a single set of reaction conditions and without materially changing the time required for forming the amide. In other words, we can produce pyrazinamide from pyrazine-2,3-dicarboxylic acid or salts of 2,3-pyrazine-dicarboxylic acid, directly in a single step, in about the same time as required for amidating pyrazinoic acid. The exact mechanism of the present invention is not known and it is

2

not desired to limit the invention to any particular theory. It seems likely, however, that there may be an intermediate formation of ammonium salt of pyrazine-2,3-dicarboxylic acid, because the reaction is not practically satisfactory with alkali metal or other salts of pyrazine-2,3-dicarboxylic acid, unless there is present sufficient ammonium salt so that presumably the pyrazine-dicarboxylic acid alkali metal salt is transformed into the corresponding ammonium salt.

10 The procedure of the reaction in the present invention is quite contrary to the normal behavior of urea with ortho-dibasic acids. Ordinarily, when ortho-dibasic acids are heated with urea, imides of the dibasic acid are formed. Thus, for example, when phthalic anhydride is heated with urea, there is formed first ortho-carboxy benzoyl urea or, if the temperature is high enough, phthalimide. Ordinarily, this reaction mechanism with urea and ortho-dibasic acids results in the production of the most stable compound and hence is the only reaction 15 which can be noted. Apparently, pyrazine-2,3-dicarboxylic acid behaves in a completely anomalous manner, since heating pyrazine-2,3-dicarboxamide is known to form the imide. If the diamide were formed as an intermediate, one would expect to obtain only the imide. 20 However, pyrazine-2,3-dicarboxylic acid does not form with urea the stable imide which ordinary ortho-dicarboxylic acids form; but it decarboxylates partially and forms the amide of the corresponding monocarboxylic acid, pyrazinoic acid. The anomalous behavior of pyrazine-2,3-dicarboxylic acid toward urea represents a striking departure from the normal behavior of ortho-dicarboxylic acid. We do not know why this anomalous behavior takes place, nor is it certain what reaction mechanism is followed: in other words, we do not know 25 whether a mono-amide is formed and then partial decarboxylation takes place, or whether the decarboxylation is effected before amidation takes place. It is also possible for other reaction mechanisms to be involved. The net result, however, regardless of what the actual reaction 30 mechanism may be, is an extremely efficient single-step process of producing pyrazinamide directly from pyrazine-2,3-dicarboxylic acid or its salts without any intermediate step of forming pyrazinoic acid.

The amount of urea to be used is in no sense critical. 35 Of course, enough urea must be used to effect the amidation. In general, it is desirable to use amounts at least approximately equimolecular. Large excesses of urea may also be employed; they do no harm; but neither do they improve the results and, therefore, while the invention is not intended to be limited in any way to an upper limit on the amount of urea to be used, in practical operation, excesses beyond approximately equimolecular amounts of the two reactants are not preferred for reasons of economy.

50 The conditions of the reaction are not at all critical. The temperatures in the reaction mixture itself may run from 105-190 or even 200° C. When bath-heated equipment is used, ordinarily the bath will have to be higher and temperatures from 200-225° C. are very 55 satisfactory with equipment of ordinary heat transfer characteristics. While the temperature is in no sense critical, we prefer to use temperatures which will result in sublimation of pyrazinamide. In other words, the equipment as a whole will operate under reflux. This permits recovering a large portion of the pyrazinamide from the cooled portions of the equipment in the form of a solid sublimate which is relatively pure, containing no substantial gross impurities. It is an advantage of the present invention that the temperature used is so un-critical, since a very careful supervision or regulation of operating conditions is entirely unnecessary, contributing therefore to smooth and simple operation with a minimum of cost of supervision.

75 The time of the reaction will vary, not only with the temperature, but as is normal, with the size of the batch. It is, however, an advantage that the time is not excessive and thus good outputs can be obtained from a given piece of equipment. Reaction times of from 4 to 6 or 8 hours will give satisfactory results 80 in suitable equipment. The invention, however, is in no sense limited to any time, the optimum time being chosen

in conjunction with the particular temperature used and the batch size, equipment and other characteristics. It is, however, an advantage that the heating time is not critical and, therefore, no control problems are involved.

It has been pointed out above that it is possible to use an alkali salt of pyrazine-2,3-dicarboxylic acid if there is present in the reaction mixture approximately equimolecular amounts of an ammonium salt such as ammonium salt of a mineral acid. This constitutes a definite advantage, since very efficient methods of preparation of the mono-potassium salt of pyrazine-2,3-dicarboxylic acid have been developed. The present invention is able to utilize this process and, therefore, even in the production of the pyrazine-dicarboxylic acid, the most effective method can be used. However, of course, the invention is in no sense limited to the method by which the pyrazine-2,3-dicarboxylic acid or its salts are prepared.

The invention will be described in greater detail in conjunction with the specific examples, the parts being by weight unless otherwise noted.

Example 1

An equimolecular mixture of pyrazine-2,3-dicarboxylic acid and urea is introduced into a bath-heated reaction vessel, the bath being maintained at about 205-210° C. As the charge heats up, the reaction mixture melts and begins to effervesce rapidly. After a while, the effervescence slows down and the sublimate appears on the cooler part of the vessel. The temperature then is raised and the reaction is completed at a higher temperature. The heating for the final completion of the reaction may, for example, take from 10-15 times as long as the heating up during the effervescent stage.

After the reaction is substantially complete, the reaction vessel is cooled to room temperature and the sublimate removed. It constitutes pyrazinamide of good quality, which can be transformed into a pharmaceutical grade by, if desired, simple recrystallization.

Example 2

An equimolecular mixture of pyrazine-2,3-dicarboxylic acid and urea is introduced into a reaction vessel provided with a reflux condenser. Ammonium hydroxide is then added to the reaction mixture in an amount approximately double that of the urea. The reaction mixture heats up to 50-60° C. and effervesces. Thereupon, the reaction vessel is heated and the mixture bubbles rapidly and the liquid refluxes in the condenser. After a short while, the reflux is terminated and the liquid is distilled out. Thereupon, the heating is continued until the reaction is substantially complete. As described in Example 1, sublimate is formed on the cooler parts of the reaction vessel and after completion of the reaction and cooling down of the vessel, the pyrazinamide is recovered from the sublimate. If desired, the residue in the reaction vessel may be heated and some additional pyrazinamide is obtained by sublimation.

Example 3

A mixture of 84 parts (0.5 mol) pyrazine-2,3-dicarboxylic acid with 90 parts (1.5 mols) of urea is prepared. The mixture is added to a reaction vessel containing 1950 parts of ortho-dichlorobenzene, the reaction vessel being equipped for agitation and reflux and the reaction vessel is heated and the reaction mixture refluxed under continuous agitation. The temperature is maintained until reaction is substantially complete. At this point, the reaction mixture is a solution containing only a small amount of solids. The hot liquid is decanted from the solids, cooled to 5° C. and the pyrazinamide which crystallizes out is filtered off.

Example 4

An equimolecular mixture of the mono-ammonium salt of pyrazine-2,3-dicarboxylic acid and urea is introduced into the reaction vessel provided with a suitable condenser. The charge is gradually heated up, melting starting at about 110° C. The heating is then increased and the temperature of the melt increases to about 160-165° C., some sublimate being formed on the cooler portions of the reaction vessel. Finally, the reaction temperature is raised to about 188° C. and maintained between this temperature and 195° C. until the reaction is substantially complete. The mixture is then cooled

and the sublimate removed. It constitutes pyrazinamide of good technical quality.

Example 5

215 parts of the mono-potassium salt of pyrazine-2,3-dicarboxylic acid hemihydrate, 180 parts of urea and 54 parts of ammonium chloride are intimately mixed and introduced into a reaction vessel equipped with a take-off condenser and provided with an inlet for inert gas, so that it can be flushed. Heating is started, the mixture melting almost at once to thick liquid which effervesces rapidly for a short time. The melt then thickens, effervescence stops and a white sublimate begins to form in the condenser. During these operations, the reaction mixture temperature has risen from 105° C. to approximately 175° C. The bath temperature for heating the reaction vessel is then increased somewhat and a slow stream of nitrogen is passed continuously through the apparatus. The internal temperature of the reaction mixture rises to about 185° C. Finally, the bath temperature is increased somewhat and the reaction carried out to as near completion as possible. A white crystalline material collects in the condenser and is removed. It constitutes pyrazinamide which can be purified by recrystallization from alcohol, if desired.

We claim:

1. As a process of producing pyrazinamide from a pyrazine-2,3-dicarboxylic acid compound having the formula

40 wherein X is a substituent selected from the class consisting of H and NH₄, the process which comprises heating said pyrazine compound with urea until pyrazinamide is formed and recovering the pyrazinamide so obtained.

2. A process according to claim 1 in which the proportions of said pyrazine-2,3-dicarboxylic acid compound and urea are approximately equimolecular.

3. A process according to claim 2 in which the pyrazine-2,3-dicarboxylic acid compound is pyrazine-2,3-dicarboxylic acid.

4. A process according to claim 1 in which the pyrazine-2,3-dicarboxylic acid compound is pyrazine-2,3-dicarboxylic acid.

5. A process of producing pyrazinamide from the mono-ammonium salt of pyrazine-2,3-dicarboxylic acid which comprises heating said mono-ammonium salt with urea until pyrazinamide is formed and recovering the pyrazinamide so obtained.

6. A process according to claim 5 in which the amount of urea is approximately equimolecular based on the mono-ammonium salt of pyrazine-2,3-dicarboxylic acid.

7. The process of claim 5 wherein said mono-ammonium salt of pyrazine-2,3-dicarboxylic acid is formed, in situ, in the reaction mixture from an alkali metal salt of pyrazine-2,3-dicarboxylic acid having the formula

75 wherein M is the alkali metal and an ammonium salt of an inorganic acid, during said heating.

8. A process of producing pyrazinamide from the mono-potassium salt of pyrazine-2,3-dicarboxylic acid which comprises heating said potassium salt with urea and a sufficient amount of an ammonium salt of an inorganic acid to transform the mono-potassium salt of pyrazine-2,3-dicarboxylic acid into the corresponding mono-ammonium salt thereof, continuing the heating until pyrazinamide is formed and recovering the pyrazinamide so obtained.

9. The process of claim 8 wherein the ammonium salt of the inorganic acid is ammonium chloride.

85

10. The process of claim 8 in which the amount of urea is approximately equimolecular based on the mono-potassium salt of pyrazine-2,3-dicarboxylic acid.

11. A process as in claim 1 in which pyrazinamide is removed from the reaction mixture by sublimation.

12. A process as in claim 1 in which pyrazinamide is removed from the reaction mixture by flushing with an inert gas.
